UNITED STATES PATENT OFFICE.

MARY LULA FRAYSER, OF HORNERSVILLE, MISSOURI.

DESIGN FOR A DISH-DRAINER.

51,061.

Specification for Design.

Patented July 24, 1917.

Application filed March 1, 1917. Serial No. 151,854. Term of patent 7 years.

To all whom it may concern:

Be it known that I, MARY LULA FRAYSER, a citizen of the United States, residing at Hornersville, in the county of Dunklin and State of Missouri, have invented a new, original, and ornamental Design for Dish-Drainers, of which the following is a specification, reference being had to the accompanying drawing, forming part thereof.

The figure is a perspective view of the dish drainer, showing my new design.

I claim:

The ornamental design for a dish drainer, as shown.

MARY LULA FRAYSER.

Witnesses:

E. G. COPE,

A. F. PARSONS.
